(57) **CLAIM**

The ornamental design for an holster clip, as shown and described.

DESCRIPTION

FIG. 1 is a perspective view of the holster clip showing the new design;

FIG. 2 is a front view of the holster clip thereof;

FIG. 3 is a rear view of the holster clip thereof;

FIG. 4 is a right side view of the holster clip thereof;

FIG. 5 is a left side view of the holster clip thereof;

FIG. 6 is a top view of the holster clip thereof; and,

FIG. 7 is a bottom view of the holster clip thereof.

The broken lines in the drawings illustrate environmental subject matter and form no part of the claimed design.

The break lines indicate that no particular length is claimed and any portion shown in between forms no part of the claimed design.
